UNITED STATES PATENT OFFICE.

FREDERICK MAX PORITZ, OF NEW YORK, N. Y., ASSIGNOR TO STAR CHANDELIER COMPANY, OF NEW YORK, N. Y., A CORPORATION OF NEW YORK.

DESIGN FOR AN ELECTRIC-CANDLE WALL BRACKET.

Application filed October 21, 1922. Serial No. 4,048. Term of patent $3\frac{1}{2}$ years.

To all whom it may concern:

Be it known that I, FREDERICK MAX PORITZ, citizen of Germany, residing at New York, in the county of New York and State of New York, have invented a new, original, and ornamental Design for an Electric-Candle Wall Bracket, of which the following is a specification, reference being had to

the accompanying drawing, forming part thereof.

The figure is a plan view of an electric candle wall bracket, showing my new design.

I claim:

The ornamental design for an electric candle wall bracket, as shown.

FREDERICK MAX PORITZ.
